UNITED STATES PATENT OFFICE

1,974,374

GAS PRODUCER GRATE

Charles Whitfield, Acton, London, England

Application March 14, 1931, Serial No. 522,743
In Great Britain January 27, 1931

5 Claims. (Cl. 126—163)

This invention relates to gas producers of the kind in which the air for limited combustion of the fuel is admitted to small separate sections of the producer grate through air-distribution chambers, having restricted air openings thereto as described in my co-pending application for patent, No. 465,966.

The invention relates more particularly to large gas producers of the above kind, to the grate of which the fuel may be supplied by one or more hoppers. In such a producer there will be a more or less constant inequality in the distribution or depth of fuel on the grate, the fuel being deeper immediately below the hopper mouth.

15 The object of the invention is to compensate for such or like uneven fuel distribution and the unequal resistance of the fuel bed for the several sections resulting therefrom.

According to the invention the gas producer 20 is of the kind in which the air for limited combustion of the fuel is admitted to small separate sections of the producer grate through air distribution chambers having restricted air openings thereto, and is characterized in that the relative 25 area of the said restricted openings, compared with that of the grate sections which they supply, is graded over the area of the grate.

In the accompanying drawings:—

Fig. 1 is a plan of one example of gas producer 30 grate made in accordance with the invention.

Fig. 2 is a sectional elevation on line 2—2 of

Fig. 1.

Fig. 3 is an underneath plan of Fig. 1.

Fig. 4 is a sectional elevation on line 4—4 of

35 Fig. 3.

As illustrated, the grate comprises bars *a* having a web *b* and overhanging grate portions *c* which constitute an upper set of laterally extending flanges. Between the webs of adjacent bars are solid ribs *d* extending to the grate surface and shown in section in Fig. 4. The air supply surface of the grate consists of transverse slits *e* in the overhanging portions of the grate surface and longitudinal slits *f* formed between the bars, the solid portions *d* forming spacing members. The air supply apertures *e* and *f* taper or open downwards in known manner for the release of ash, etc. The ends of the bars and the side bars are formed with a flange *g* by which 50 they are supported in the frame *h* of the grate.

Between the webs *a*, which are formed with a small head at their lower edge, are positioned slides *i* which are shown with clearance but are as close a fit as is practically possible against the 55 lower ends of the ribs *d*. The slides *i* fit against

and are supported upon a lower set of laterally extending flanges formed by the bars *a* projecting beyond the webs *b*. In the slides are holes *j* forming the restricted air inlet passages to the chambers *k* formed between the webs *a* and the ribs *d*. The slides are shown with one hole *j* for each chamber, the holes being graded in size so that those for the inner chambers are larger than those for the outer chambers. A plurality of smaller holes may be used and their number varied so that their total areas are similarly graded.

The same effect of grading for the restricted inlets can be obtained by varying the size of the chambers and having the holes *j* all the same size. The disadvantage of such a form however would be obviously that each bar would have to be different. The slides *i* are intended to be always in, as shown, while the grate is working, but can be withdrawn to release ash, etc., from the chambers.

75 The arrangement shown is suitable for a grate having a single central feed hopper which would give a normal inequality of depth of fuel on the grate, the fuel bed being thinner towards the outer sections. This arrangement provides for a greater restriction of the air supply to the outer or side sections of the grate where the fuel bed will be shallower than on the central sections immediately below the hopper, and this greater restriction will be proportioned so as to compensate for the difference of resistance of the fuel bed to the passage of the air.

80 The natural fall of the fuel on to the grate will ensure a more or less constant inequality in the depth of the fuel and hence the resistance of the fuel bed and the required grading or difference of restriction of the air openings can be easily ascertained experimentally or otherwise.

85 Obviously, where two or more hopper feeds are provided or where other conditions make grading desirable, the areas of grading for the restricted air openings will be arranged accordingly.

90 What I claim is:—

1. A grate for a gas producer consisting of a 100 plurality of adjacent girder-like bars, upper and lower flanges extending laterally from the sides of said bars, apertures in and between upper flanges of adjacent bars for feeding air to fuel supported thereon, transverse webs extending laterally from said bars at predetermined distances therealong, the webs of adjacent bars forming end closures and partitions, slideable plates resting upon the lower flanges of adjacent 105 bars and co-operating with said webs to form chambers between adjacent bars, air inlet aper- 110

- tures in said plates of graded size, the smaller apertures being for chambers in the outer portions of the grate and increasing in size for chambers located nearer the center portion of the grate, the inlet area of any chamber being considerably less than the area of grate apertures for that chamber. 80
2. A grate for a gas producer provided by a grate assemblage constructed and arranged so as to have an upper fuel supporting surface with subdivided air chamber sections below said fuel supporting surface, and so as to have lower apertured members for completing the floors of the air chamber sections, the fuel supporting surface having air outlet apertures therethrough leading from the chamber sections, the apertures in the lower members providing air inlet passageways or openings leading to the air chamber sections, the total area of the air inlet passageway for each chamber section being considerably less than the total area of the air outlet apertures leading therefrom, the air inlet passageways being graded whereby the relatively larger air inlet passageways are provided for the centrally located air chamber sections. 85
3. A grate for a gas producer having grate bars providing an upper fuel supporting surface with subdivided air chamber sections below the fuel supporting surface, said grate having lower apertured plates providing floor members for the chamber sections, the fuel supporting grate surface having air outlet apertures therethrough leading upwardly from the chamber sections, the apertures of the lower plates providing air inlet openings leading upwardly to the chamber sections, the total area of the air inlet aperture for each chamber section being considerably less than the total area of the air outlet apertures for the corresponding chamber section, the air inlet apertures being graded as to relative area for the several chamber sections whereby the larger air inlet apertures are provided for the centrally located chamber sections. 90
4. A grate for a gas producer consisting of a plurality of adjacent girder-like bars, upper and lower sets of flanges extending laterally from the sides of said bars, apertures in and between one set of the flanges of adjacent bars for feeding air to fuel, transverse webs extending laterally from said bars at predetermined distances therealong, the webs of adjacent bars forming enclosures and partitions, slideable plates fitted against the other set of flanges of adjacent bars and cooperating with said webs to form chambers between adjacent bars, air inlet apertures in said plates of graded size, the smaller apertures being for chambers in the outer portions of the grate and increasing in size for chambers located nearer the center portion of the grate, the inlet area of any chamber being considerably less than the area of grate apertures for that chamber. 95
5. A grate for a gas producer comprising a fuel-supporting member formed interiorly with a plurality of separate chambers, said member having air outlet apertures in its upper face extending from each of said chambers and having air inlet apertures in its lower face extending from each of said chambers, the total area of the said air inlet apertures for each chamber being not more than one-third of the total area of the said outlet apertures for the same chamber, and the ratio of area of the inlet apertures relative to that of the outlet apertures for the outer chambers of the grate being smaller than such ratio for the center chambers of the grate. 100
